CUSHION SHOE

Francis M. Gilkerson, St. Louis, Mo., assignor of
one-half to Paul H. Gilkerson, St. Louis, Mo.

Application March 30, 1935, Serial No. 13,803

2 Claims. (Cl. 36—17)

The invention relates to shoes and more particularly to shoes having a cushion sole.

The main object of the invention is to provide a shoe in which the inner sole is stitched to a 5 welt and the inturned edge of the upper and a cushion member is interposed between the inner sole and the outer sole and firmly secured in place to the soles and to the welt and prevented from buckling.

10 A further object of the invention is to provide a welt type of shoe in which a soft cushioning member, such as sponge rubber, extends to the edge of the soles and prevents the formation of a hard ridge where the fastening means connects 15 the inner sole with the upper and the welt.

The invention further consists in the several features hereinafter set forth and more particularly defined by claims at the conclusion hereof.

In the drawing:

20 Fig. 1 is a side elevation of a shoe embodying the invention, parts being broken away and parts being shown in section;

Fig. 2 is a detail vertical sectional view through the forepart of the shoe;

25 Fig. 3 is a detailed vertical sectional view through a heel seat portion of a shoe embodying the invention.

In the drawing, the numeral 4 designates a shape-determining inner sole, 5 the upper with its lining 6, and 7 a welt. This welt 7 may extend around the entire shoe in the case of a shoe having a sewed heel seat or it may terminate at the breast of the heel in a shoe having a nailed heel seat.

30 The outsole 8 is secured to the welt 7 in the usual manner as by stitching 9 or other suitable fastening means.

35 A soft cushioning member or filler 10 formed of one or more parts or plies is interposed between the inner sole 4 and the outsole 8 and is firmly fastened at all points or at least over such an area to the under side of said inner sole and to the adjacent side of the outsole by suitable adhesive, cement or vulcanizing so as to cause the parts to act as a unit. In a laminated or 40 ply construction of cushion member one of the laminations may be substantially the same thickness as the welt.

45 It is to be noted that the cushion 10 is substantially the same size as the inner sole and may extend over the forepart of the shoe or over the entire sole area including the heel seat, and it, therefore, has a part or marginal edge 11 which is interposed between the inner sole and the inturned edge of the upper and its lining at

the forepart of the shoe, and, if extended to the heel, the upper, lining, and counter at the heel seat of the shoe.

The inner sole 4, the welt 1, and the inturned upper are secured together at the forepart of the shoe to the breast of the heel by stitching or other suitable fastening means 12. These fastening means pass through the marginal edge 11 of the cushion and thus firmly secure it to the other parts of the shoe so that it will flex therewith and prevent buckling of the inner sole. This cushion 10 is of soft rubber, such as sponge rubber and it, therefore, acts as a cushion between the insole and the inturned edge of the upper and eliminates the usual hard ridge 15 around the edge of shoes of this general type. Furthermore, since this cushion member is cemented to the outer and inner sole the whole assembly acts as a unit, and there is no possibility of the filler or cushion member slipping or sliding and thus further preventing any tendency of the parts to buckle.

20 A metal shank stiffener 13 may be mounted in the shank of the shoe between the outer sole and the cushion.

25 It has been previously pointed out that the forepart construction above described may be used in a shoe having either a sewed heel seat or a nailed heel seat. Where the heel seat is a sewed heel seat, the construction of the heel portion of the shoe is identical with the forepart except that the usual counter is associated with the upper at the heel seat and stitched with the lasted over edge to the inner sole, the cushion, and the welt by the stitching 12. As illustrative of a nailed 30 heel seat construction, a detailed view has been shown in Fig. 3 in which the upper 5, lining 6, counter 14, have their inturned edges secured to the inner sole 4 and the cushion member 10 by the stitching 12 or any suitable fastening means. 35 The outer sole 8 at the heel seat may have a random section 15 so as to provide for a cavity 16 of greater depth than the spaces between the outer sole and the inner sole throughout the remainder of the shoe and into which a portion of the 40 cushion fits. The outer sole is here shown as secured by fastening means, such as nails 17, passing through the inturned edges of the upper, counter, and lining, and the marginal edge of the cushion 10 and clinched at the inner sole 4. 45 The rubber heel 18 may be secured to the outer sole at the heel seat in any suitable manner, and one well known way is by nails 19 which pass through the outer sole portions, the inturned edges of the upper, counter, and lining, the outer 50

55

edge portion of the cushion, and into and clinched into the inner sole 4.

I desire it to be understood that this invention is not to be limited to any particular form or arrangement of parts except insofar as such limitations are inclined in the claims.

What I claim as my invention is:

1. In a cushion shoe, the combination of a shape-determining inner sole, an upper, an outer sole, a welt, a resilient cushion member coextensive with and cemented to the bottom side of the insole at the forepart of the shoe and cemented to the outsole at the forepart over a sufficient area so as to cause the sole members to act as a unit, 10 the upper having a lasted over edge at the forepart overlapping the outer edge portion of said cushion member, means passing through and securing together said inner sole, outer edge portion 15 of said cushion member, lasted over edge of said

upper and the welt, and means securing said outer sole to said welt at the forepart of the shoe.

2. In a cushion shoe, the combination of a shape determining inner sole, an upper, an outer sole, a welt, a soft rubber cushion member coextensive with and cemented to the bottom side of the insole at the forepart of the shoe and cemented to the outsole at the forepart over a sufficient area so as to cause the sole members to act as a unit, 10 the upper having a lasted over edge at the forepart overlapping the outer edge portion of said cushion member, stitching securing together said inner sole, outer edge portion of said cushion member, lasted over edge of said upper and the welt, said outer sole also being secured 15 to said welt beyond the lasted over edge of said upper.

FRANCIS M. GILKERSON.
